CLAIM

The ornamental design for a lawnmower, as shown and described.

DESCRIPTION

FIG. 1 is a front perspective view of a left side of the lawnmower with a bagger attachment;

FIG. 2 is a front perspective view of a right side of the lawnmower of FIG. 1;

FIG. 3 is a right side view of the lawnmower of FIG. 1;

FIG. 4 is a left side view of the lawnmower of FIG. 1;

FIG. 5 is a top view of the lawnmower of FIG. 1;

FIG. 6 is a front view of the lawnmower of FIG. 1;

FIG. 7 is a rear view of the lawnmower of FIG. 1;

FIG. 8 is a bottom view of the lawnmower of FIG. 1;

FIG. 9 is a rear perspective view of a portion of the lawnmower of FIG. 1;

FIG. 10 is a left perspective view of the portion of the lawnmower of FIG. 9;

FIG. 11 is a top view of the portion of the lawnmower of FIG. 9;

FIG. 12 is front perspective view of a portion of the lawnmower of FIG. 1;

FIG. 13 is a front perspective view of a portion of the lawnmower of FIG. 1;

FIG. 14 is a rear, downward view of a portion of the lawnmower of FIG. 1;

FIG. 15 is a rear perspective view of a left side of the lawnmower of FIG. 1 as seen in a first condition without the bagger attachment, wherein the first condition includes covers positioned in closed orientations relative to battery compartments;

FIG. 16 is a rear perspective view of a left side of the lawnmower of FIG. 1 as seen in a second condition without the bagger attachment, wherein the second condition includes no covers on the battery compartments;

FIG. 17 is a top view of the lawnmower of FIG. 1 as seen in the second condition without the bagger attachment;

FIG. 18 is a rear perspective view of a portion of the lawnmower of FIG. 1 as seen in the second condition without the bagger attachment;

FIG. 19 is a rear perspective view of a portion of the lawnmower of FIG. 1 as seen in a third condition without the bagger attachment, wherein the third condition includes no covers on the battery compartments and no cover on an electrical charging port of the lawnmower;

FIG. 20 is a rear view of the lawnmower of FIG. 1 as seen without the bagger attachment;

FIG. 21 is a front perspective view of the lawnmower of FIG. 1 without the bagger attachment;

FIG. 22 is a rear perspective view of a right portion of the lawnmower of FIG. 1 without the bagger attachment; and,

FIG. 23 is a right side view of the lawnmower of FIG. 1 without the bagger attachment.

The broken lines illustrate portions of the design that form no part of the claim.
